UNITED STATES PATENT OFFICE.

AXEL WASBERG AND WILLIAM W. DARROW, OF CHICAGO, ILLINOIS, ASSIGNORS TO
CAMEL COMPANY, OF CHICAGO, ILLINOIS, A CORPORATION OF ILLINOIS.

CORNER ENTRANCE IN HOUSE CARS.

Application filed April 16, 1926. Serial No. 102,399.

This invention relates to a house car construction for railroad trains and concerns itself primarily with an entrance and closures therefor whereby automobiles, busses and trucks, with long chassis can be easily loaded or unloaded under their own power from side platforms, and in which other bulky lading can also be easily loaded or unloaded.

It has been the common practice to provide such house cars with a pair of end doors which are respectively hinged to the outer parts of the ends and which swing outwardly, whereby substantially the whole end of the car consists of a pair of doors. This construction materially weakens the car structure, and when the car is used for transporting such lading as dressed lumber or cold rolled shafting, or the like, the shunting of the cars in transit often shifts the load endwise and projects the same through the weakened end door structure.

Moreover, it is also impossible to load such cars with vehicles from side platforms. The usual practice in such cases is to spot a flat car between two cars having end doors. The vehicles under their own power would then be run from the side platforms to the flat car, which serves as an intermediate platform from which the vehicles could be run through the end doors and into the house cars. The use of a flat car for such a purpose and the labor and time required for spotting the same involves an expensive procedure.

It is an object of this invention to provide a house car of such construction that automobiles and the like may be readily loaded under their own power from a side platform, thereby eliminating the use of a flat car.

It is a further object of this invention to provide an end structure for cars which may be partially opened, but which does not impair the efficiency of the car for transporting other lading than vehicles.

It is a still further object of this invention to construct house cars so that vehicles under their own power, may be run into the car from side platforms upon both sides of the car, and that the same may also be run into a second series of cars parallel to the first series, commonly known as gang loading.

It is a still further object of this invention to provide such loading entrances without

interfering with the standard hand brake, rigging and ladder.

Some of these objects may be attained by providing a corner entrance in the car and closing means therefor comprising a section forming a part of the end of the car, and a section forming a part of the side of the car, which sections are securely anchored to the car to maintain a rigid end structure. More specifically these objects may be attained by making the sections as two separate doors which may be opened for the entrance of vehicles and which may be closed and firmly anchored in closed position for constituting a part of the car wall.

Other objects may be attained by providing two diagonal corners of the car with proper doors, especially when gang loading is contemplated.

Other objects and the attainments thereof will become more apparent in the following description and disclosures.

This invention comprises the novel structure and combinations hereinafter described and more particularly pointed out and defined in the appended claims.

In the accompanying drawings, which illustrate a preferred embodiment of this invention and in which similar reference numerals refer to similar features in the different views:

Figure 1 is an end elevational view of a house car of the A. R. A. type, double sheathed type, embodying this invention.

Figure 2 is a fragmentary side elevational view of a house car embodying this invention.

Figure 3 is an enlarged fragmentary horizontal sectional view taken through the corner structure of the car, embodying this invention.

Figure 4 is an enlarged fragmentary side elevational view illustrating the locking arrangement for a portion of the removable closure for the car.

Figure 5 is an enlarged sectional view taken upon the line V—V of Figure 3 with parts in elevation.

Figure 6 is an enlarged fragmentary sectional view taken through the corner structure of the door and looking upwards, illustrating certain internal locking mechanism.

Figure 7 is a fragmentary side elevational view illustrating the gusset connection between the end plate and side plate and the

interlocking relationship of the side plate and a movable part of the closure.

Figure 8 is a fragmentary elevational view with parts in elevation looking from the inside of the car in the direction of the end of the car with the end door closed.

Figure 9 is a fragmentary top plan view illustrating a track and stop arrangement of a flush type of sliding door.

Figure 10 is an enlarged sectional view taken upon the line X—X of Figure 9, looking in the direction of the arrow.

Figure 11 is an enlarged sectional view taken substantially upon the line XI—XI of Figure 9 looking in the direction of the arrow, with door closed.

Figure 12 is an enlarged sectional view taken upon the line XII—XII of Figure 9 looking in the direction of the arrow, the door being shown open.

Figure 13 is an enlarged fragmentary vertical sectional view taken through the side plate and track of the car illustrating the mechanism for operating the flush door in and out of closed position.

Figure 14 is a fragmentary top plan view taken upon the line XIV—XIV of Figure 13.

Figure 15 is a fragmentary horizontal sectional view taken through the end of the car showing both the end and side door open and illustrating in dotted lines the manner of loading an automobile.

Figure 16 is a sectional diagrammatical view through the corner of a car, illustrating the manner in which the door opening may be varied.

Figure 17 is a diagrammatical plan view illustrating the method of loading automobiles, trucks, etc. from a side platform into a train of box cars according to this invention.

Figure 18 is a diagrammatical plan view illustrating a method of group loading both from a side platform and also from an island platform according to this invention.

In carrying out this invention, a house car is provided with one or more corner entrances, and means are provided for closing such entrance or entrances. While this means may assume various forms, it is generally characterized by the fact that a portion of the means constitutes a part of the end of the car and another portion of said means constitutes a part of a side of the car.

In the present exemplification of this invention, the closing means are shown as consisting of a pair of doors, which may be mounted to swing or slide, or one of which may be mounted to swing and the other to slide. In the drawing, the end door is mounted to swing on suitable hinges while the side door is mounted to slide on rollers.

The cars may be equipped with one cor-

ner entrance or two diagonally opposite corner entrances. In referring to Figure 6, it will be noted that adjacent the hinged edge of the door, 1, there is a jamb post 2 which constitutes a part of the rigid car end. A second post filler 3 is positioned beyond the post 2 and a Z bar 4 has its web positioned between these posts, with one flange lying against the outer surface of the post 2, and the other flange positioned against the inner surface of the post filler 3. A suitable sheathing 5 or the like forms the closure for the rigid section of the car end, and beneath this sheathing, are upper and lower gusset plates 6 (Figure 1). Each gusset plate 6 has a flange riveted to the web of the Z bar 4. The upper edge of the upper plate 6 is riveted to the end plate of the car, while the lower edge of the lower gusset 6 is riveted to the end sill 17 of the car. This construction produces a strong, rigid and durable end structure for supporting the hinged end of the door 1, which may be attached thereto by suitable hinges 1^a (Figure 1).

The end door 1 has a Z bar 7 attached thereto by one of its flanges. The web and other flange of this Z bar fit against the post 2 when the door is in closed position. A post filler 8 is carried by the rear end of the door 1, the post fitting within the angle of the Z bar. Upon the front end of the door 1, there is attached a Z bar 9, the web of which projects inwardly and the free flange of which carries a jamb post 10, (Figures 3 and 6), bolted thereto. The outer rear corner of the jamb post 10 is rabbeted as indicated at 11 for receiving the front end of the side door 12.

Mechanism has been provided for anchoring the end door in closed position to the top and bottom of the car. This mechanism may also take various forms provided it produces a sufficiently rigid end structure. However, in the present embodiment of this invention, this anchoring mechanism consists of a lower socket member 13 secured to the side and end sill of the car, an upper socket member 14 (Figures 7 and 8), secured to the side and end plate of the car, upper and lower latch bolts 15 which fit in said socket members, and jaw members that engage the socket members as will later more fully appear. It will be noted that the lower socket member 13 is formed on a plate 13^a secured to the side sill 16 and the horizontal flange of the angular end sill 17, and is provided with an outlet channel 18 for the escape of dirt from the socket.

The locking bolts 15 are normally held in hollow bearings 19 attached to the end door 1. Each bearing 19 has a pair of clamping jaws 20 which take over the head of the adjacent socket. For this purpose the free ends of the socket members 13 and 14 are respectively provided with suitable enlargements 130

ments 13^a and 14^a, which are formed by laterally projecting flanges or portions on the sides of the sockets, producing a form of T-head.

- 5 The lower bearing 19 is formed of a casting having a flange 21 attached to the door 1, a flange 22 attached to the web of the Z bar 9, and a base portion 23 secured to the horizontal flange 24 of an angle iron 25 extending along the lower portion of the door. The upper bearing 19 is similarly constructed and similarly attached. It will be noted that the said horizontal flange 24 is of a sufficient height to clear the end sill 17 when 10 the end door is closed. The sheathing 5, however, extends below such horizontal flange for contacting relation with the vertical flange of the side sill when the end door is in closed position.
- 15 The bolts 15 are pivoted to suitable operating rods 26 which may be operated from within the car for locking and unlocking the end door. The manner in which the operating rods 26 may be secured has not been 20 illustrated since it is contemplated that any well known method may be used.

The aforementioned side door 12 may be constructed of any suitable material. In the present instance, it comprises a pair of lateral Z bars 27 between which upright timber planks are secured as shown in Figures 2 and 3. The outer flange of the front Z bar 27 wedges under an inclined flange 28 on an angle iron 29 secured to the Z bar 9 on 30 the end door. The rear end Z bar of this side door fits in a corresponding angle 30 of a metal lining 31 surrounding a portion of a post 32 at the rear end of the side door opening. The post 32 is suitably rabbeted upon 35 its forward outer corner to form the angular recess 30. Obviously, the side door is flush with the side of the car, and it must be so mounted that it can be swung outwardly and slid upon its supporting rollers. While 40 such flush doors and the operating mechanism therefor are old, we have illustrated in Figures 9 to 14, the mechanism for supporting and operating such a door.

In referring to said Figures 9 to 14, it will 45 be noted that the roller track 33 converges toward the end of the car where the side door 12 is located. The side door is supported upon the track 33 by a pair of rollers 34 and 35, the former of which is mounted 50 on a stationary bracket or hanger 36, while the latter is mounted upon a swingable hanger or bracket 37 pivoted at its lower end to the door as indicated at 38.

The mechanism for swinging outwardly 55 is shown in Figures 13 and 14. The same comprises a rod 39 rotatably secured to the rear part of the side door by suitable bearing straps 40 and provided with an operating handle 41, (Figure 2) at its lower end 60 which may be latched to the door as shown

in Figure 2. The upper end of the rod 39 is provided with a crank arm 42 which has a terminal wrist pin 43 engaging in a slot 44 of a clip or device 45, having a groove or guideway 46 in which the lower margin of the rail 33 extends. It will readily be apparent, that by rotating the rod 39, the door 12 can be swung outwardly beyond its confining recess so that it can be operated to 70 open position.

In Figure 15, there is shown a sectional view with the doors 1 and 12 in open position and an automobile being driven into the car through the opening afforded by the said doors.

The opening space afforded by the doors 1 and 12 may have different relative positions by properly proportioning the doors as shown in Figure 16. In referring to said figure, it will be obvious that the door 1 may have the width of the line A₁, while the door 12 may have the width of the line A₂, or the door 1 may have the width of the line B₁, while the door 12 has the width of the line B₂. By a further variation, the end door may have the width denoted by the line C₁, while the side door has the width denoted by the line C₂.

In Figure 16, the widths A, B and C of the different openings are substantially the same, a different angularity is however afforded by each different arrangement for loading lading from the side platform. Such width may however be changed as desired.

In Figure 17, there is shown a pair of house cars 47 equipped with corner entrances having doors 1 and 12. The cars are positioned adjacent a side platform 48 and in dotted lines are shown vehicles 49, some of which are already positioned in the cars while the others are entering. The simplicity and ease with which these cars can be loaded is obvious from this disclosure.

In Figure 18, there is shown an island platform 50 with a train of cars 51 upon one side having corner entrances in accordance with this invention. Along the other side of the island platform, are shown two parallel trains of cars 52 and 53, certain cars of which have corner entrances at diagonally opposite corners. These corner entrances are equipped with the doors 1 and 12 as previously described.

It will be noted that if the cars in the trains 52 and 53 are properly arranged, the vehicles may be run from one to the other under their own power. Of course, it is contemplated that proper bridging from one train of cars to the other be provided. Thus the vehicles 54 in dotted lines, are shown passing from one train of cars to the other, commonly known as gang loading. In order to practice this form of loading it is however necessary to provide certain of the cars

with corner entrances at two diagonally opposite corners.

When it is desired to load grain in the box cars, it is necessary to provide a grain door in connection with the side door 12. For this purpose a pair of Z bars 56 (Figure 3) may be applied upon the posts 10 and 32 for forming a guideway for receiving the boards or the like that form the grain door.

10 It will be appreciated that this invention will greatly facilitate the loading and unloading of vehicles and other bulky matter, and save a great deal of time and labor. It will also be appreciated that since the end 15 door only occupies a portion of the end of the car and is firmly anchored to the top and bottom of the car in its closed position, the end of the car will not be materially weakened.

20 We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. A house car having a corner entrance, and means for closing said entrance comprising a section constituting a portion of an end of the car and a section constituting a portion of one side of the car, and means for releasably securing said sections in substantial alignment with the rear end of the car 35 and one side of the car.

2. In a house car having a corner entrance, means for closing said entrance comprising a section constituting a portion of one end of the car and a section constituting a portion of one side of the car, and means for releasably anchoring said sections to the car when the same are in closed position.

3. A house car having a corner entrance, means for closing said entrance comprising a 45 movable section constituting a portion of an end of the car and a movable section constituting a portion of a side of the car, and means for connecting said sections and securing the same in closed position.

50 4. In a house car, a corner construction embodying a pair of doors at right angles to each other, and corner means for securing and anchoring said doors in closed position.

5. In a house car, a corner construction 55 comprising a pair of cooperating doors normally at right angles to each other, one door being swingable and the other door being slideable, one door carrying a jamb for co-action with the other door, and means for 60 releasably anchoring said jamb in door closing position.

6. A house car having a corner entrance of a width to allow a vehicle to enter under its own power, an end door and a side door 65 for closing said entrance, and a common

jamb member for securing said doors in closed position.

7. In a house car, a corner construction comprising a pair of doors, one door being connected to one end of the car, and the other door being connected to the side of the car, and jamb means for connecting the meeting ends of said doors. 70

8. A house car having a corner entrance, a pair of doors for closing said entrance, one door being supported upon one end of said car and the other being supported upon one side of said car, one of said doors having a right angled corner. 75

9. A house car having a corner entrance, 80 a pair of doors for closing said entrance, one door being hinged to an end of the car and the other being slidably mounted upon a side of the car, and a jamb carried by one door for coacting with the other door when the same are in closed position.

10. A house car having a corner entrance, a pair of doors for closing said entrance, one door being hinged upon an end of the car and the other door being slidably mounted upon the adjacent side of the car, and a jamb carried by said hinged door for coaction with the front end of the sliding door. 90

11. A house car having a corner entrance, 95 means for closing said entrance comprising a hinged door, upper and lower socket members on the car, bolt sheathes carried by said door and having means for engaging over said socket members, and latch bolts carried by said sheathes for entering said socket 100 members.

12. A house car having a corner entrance, means for closing said entrance comprising an end door and a side door, means for anchoring one door with respect to the top 105 and bottom of the car, and a jamb carried by said last mentioned door for supporting the front end of the other door.

13. A house car having a corner entrance, means for closing said entrance comprising 110 a door having a hinged connection with the car, means for anchoring said door with respect to the top and bottom of the car comprising inter-engaging members, and latching means for latching said members against 115 lateral movement.

14. A house car having a corner entrance, means for closing said entrance comprising a section constituting a part of an end of the car, and a section constituting a portion of the adjacent side of the car, means for anchoring one section with respect to the top and bottom of the car comprising cooperative members, and latching means for coupling said cooperative members against 120 lateral movement. 125

15. A house car having a corner entrance, a pair of doors for closing said entrance, means for anchoring one door to the top and bottom of the car comprising a pair of co- 130

operative members adapted to be brought into interlocking engagement when said last mentioned door is closed, latch bolts for coupling said members against lateral movement, and a jamb carried by said last mentioned door for receiving the front end of the other door.

16. A house car having a corner entrance, means for closing said entrance comprising a door hinged to one end of the car and a door slidably mounted upon one side of the car, a pair of latch bolt bearings having projecting claw members carried by said hinged door, headed socket members carried by the top and bottom of the car and adapted for engagement by said claw members when said hinged door is closed, latch bolts carried by said bearings for engaging said socket members, and a jamb carried by said hinged door for supporting the front end of the side door.

17. A house car having a corner entrance, means for closing said entrance comprising a door hinged to one end of the car and a door slidably mounted upon the side of the car, means for anchoring said hinged door to the top and bottom of the car, means for latching the same against lateral movement, and a jamb carried by said hinged door for forming an abutment for the front end of the side door.

18. In a house car having a pair of diagonally opposite corner entrances, a pair of doors for closing each entrance whereby a

thoroughfare is provided through said car. 35

19. In a house car having diagonally opposite corner entrances, a pair of doors for closing each entrance, means for anchoring one door of each pair to the top and bottom of the car, and a jamb post carried by the 40 anchored door for cooperating with the other door.

20. In a house car having diagonally opposite corner entrances, a pair of doors for closing each entrance, one door of each pair 45 constituting a portion of an end of the car, and the other door of each pair constituting a portion of the side of the car, and means for anchoring one door of each pair to the top and bottom of the car.

21. A house car having a corner entrance, means for closing said entrance comprising a movable section and means for anchoring said section to the top and bottom of the car for forming a part of the car wall. 55

22. A house car having a corner entrance adapted for admitting vehicles under their own power, means for closing said entrance comprising a door having a hinged connection with the wall of the car, and cooperating means on said door and upon the top and bottom part of the car for anchoring said door in closed position for forming a part of the car wall. 60

In testimony whereof we have hereunto 65 subscribed our names.

AXEL WASBERG.

WILLIAM W. DARROW.
